FREDERICK WILLIAM RASMUSSEN, OF PAHIATUA, NEW ZEALAND.

AUTOMATICALLY-FOLDING SEAT.

1,141,724.

Specification of Letters Patent. Patented June 1, 1915.

Application filed July 28, 1914. Serial No. 853,611.

To all whom it may concern:

Be it known that I, FREDERICK WILLIAM RASMUSSEN, subject of the King of Great Britain, residing at Pahiatua, New Zealand, 5 have invented a new and useful Improved Automatically-Folding Seat; and I do hereby declare the following to be a full, clear, and exact description of the same.

This invention has been designed in order 10 to provide a folding seat for use in milking sheds or other places that, when not in use, will automatically fold up alongside a wall or other structure so as to be out of the way and at the same time be convenient for 15 use. When used in milking sheds (for which the seat has been particularly designed) the seat will take the place of the ordinary milking stool and will be free from the objections surrounding the use of the 20 stools owing to their liability to be dirtied while in the byre and the necessity of handling them to remove them or place them in position.

The seat is formed by a back portion and a 25 seat portion the latter of which is at its inner end, hinged to the lower end of the back in such a manner as to permit of it turning out at right angles thereto, or of folding in against it. The seat is suspended from a 30 horizontal bar by means of a metal frame consisting of a pair of loops arranged on the bar, one on each side of the seat, and a stirrup connection that extends down to and across beneath the seat portion through 35 bearings thereon. It is also formed with a rearwardly extending guide that passes across behind the back and loosely holds the back between itself and the bar. This frame is so disposed that when the seat is left free, 40 the weight of the seat will cause its back to drop and the seat portion to turn up against the back and thereby keep the seat in the folded condition.

In the accompanying drawings:—Figure 45 1 is a front view, and Fig. 2 a side elevation of the seat in the position for use. Fig. 3 is a side elevation of the seat in the normal collapsed or folded condition. Fig. 4 shows an alternative construction.

50 A' is the back portion and B the seat portion both of which are made of the necessary size and shape and which are hinged together, as at B', so as to be capable of folding up against one another as shown in Fig.

3 or of opening out at right angles as shown 55 in Fig. 2.

C are the loops of the supporting frame, such frame being made by the bending of a single length of light round iron bar, first to form the stirrup D passing beneath the seat 60 portion B and up on each side thereof, then the loops C, and then the guide frame E encircling the back A of the seat, as clearly shown by the drawings. When the seat is placed against a wall or other fixture, this 65 guide frame will not be required, the back of the seat in such a case being supported by resting against the wall. The construction will then follow that shown in Fig. 4, the loops C being held from spreading by means 70 of the stay bar C' extending across the front. The stirrup portion D as it passes beneath the seat B, is pivoted thereto by the staple or like bearings D' arranged at a suitable distance out from the hinge to carry the seat 75 and the weight placed thereon. The loops C are made large enough to fit loosely over the bar F which is arranged horizontally 80 along the side of the byre, or wall or other fixture, being carried at its ends by suitable brackets G. This bar therefore serves to support the seat and it is preferably made of sufficient length to allow of the seat being moved to and fro along it and thereby 85 adjusted in its position. A number of seats 90 may, if desired, be supported upon the same bar, in cases where a row of seats is desired, e. g. the back row of seats in a public hall, or a row of seats in a dining room. The suspension of the seat upon the bar in this 95 manner will therefore cause the weight thereof to move the back A down through the guide E and the seat B to fold up on to its front owing to the stirrup D. When the seat is to be occupied, the seat portion B is turned out and down which causes the back A to slide up through the guide E. The seat B is then prevented from turning 100 down below the right angled position by the engagement of the overlap on the seat portion with the bottom end of the back and by the engagement of the stop A' formed on the back with the underside of the bar F. This stop may be made in any suitable manner, in the drawings it is formed by the shoulder 105 made by decreasing the thickness of the upper portion of the back. When the seat is freed from the weight of the person sit-

ting thereon, it will automatically resume its normal folded position.

What I do claim as my invention, and desire to secure by Letters Patent is:—

5 1. An automatically folding seat comprised by a back portion having a seat portion hinged to its lower end and a suspending frame consisting of a horizontal bar, loops encircling the bar one on each side of 10 the seat back and a stirrup connection with the loops underlying and pivoted to the seat portion, substantially as specified.

2. An automatically folding seat comprised by a back portion having a seat portion hinged to its lower end so as to fold 15 thereon and a suspending frame consisting of a horizontal bar, loops encircling the bar, one on each side of the seat back, a stirrup connection with the loops underlying and 20 pivoted to the seat portion and a guide con-

nection with the loops encircling the seat back, substantially as specified.

3. An automatically folding seat comprised by a back portion having a seat portion hinged to its lower end, and a suspending frame 25 consisting of a horizontal bar, and a stirrup underlying and pivoted to the seat portion and extending upward on both sides and loosely encircling such horizontal bar, and a stop projecting forwardly from 30 the back portion and underlying the horizontal bar, substantially as specified.

In testimony whereof, I have signed this specification in the presence of two subscribing witnesses.

FREDERICK WILLIAM RASMUSSEN.
